FOOD WARMER

Jerome P. Heilweil, Wynnewood, Pa.
(Trenton Ave. and Ann St., Philadelphia, Pa.)

Filed Nov. 10, 1959, Ser. No. 58,294

Term of patent 14 years

(Cl. D81—10)

Fig. 1 is a front perspective view of a food warmer embodying the design; and

Fig. 2 is an end elevational view thereof.

The rear of the food warmer is substantially plain and the undisclosed end is a mirror image of the end shown in Fig. 2.

I claim:

The ornamental design for a food warmer, as shown and described.
